OIL BURNER

Jerome J. Sloyan, Red Bank, N. J.

Application December 13, 1930, Serial No. 502,055

4 Claims. (Cl. 158—76)

This invention pertains to the general class of heating devices and particularly to the class of heating devices adapted for burning liquid fuels.

5 The invention will be described in connection with a particular type of oil burner. However, it is understood that the invention in whole or in part may be applied generally to the burning of liquid and other fuels.

10 There are many types of oil burners in use at the present time. Many of these burners, however, are not adapted to be started with fuels of low volatility; are not automatic in starting and require considerable attention and regulation in 15 starting; develop fuel difficulties such as flooding of the carburetor or mixer, flame extinction, etc.; are not adapted to positively ignite the fuel; are not sufficiently proof against pre-ignition of the fuel and/or are in some other features generally unsatisfactory. Many burners employ a 20 diaphragm of reticular material such as wire cloth in the path of the fuel mixture to prevent propagation of the flame back into the mixing device and/or source of fuel. Devices of this 25 character have a tendency to clog or choke due to the deposition of incombustible particles in or about the interstices of the diaphragm. Such diaphragms also have a tendency to burn out due to the fact that the flame is in contact there- 30 with during practically all low rates of burning.

In my invention a fuel of low volatility and of 35 low grade may be used throughout its operation including that of starting; the apparatus requires no attention during operation; starts automatically; ignites the fuel positively; shuts down automatically if flame or fuel difficulties develop; and although it pre-heats the air to a 40 temperature consistent with highest efficiency it does not pre-heat the air to a point where pre-ignition may occur. Expansion joints are provided to allow for unequal expansion of the parts and novel means are provided for attaching certain of the parts together. Novel means are also provided for enriching the fuel for starting.

45 In the drawings wherein one form of the invention is shown merely for the purpose of illustration;

Figure 1 is an elevation, chiefly in section, of one form of the device.

50 Figure 2 is an end view.

Figure 3 is a section on line 3—3 of Figure 1.

Referring to Figures 1, 2 and 3, at 10 is shown a furnace wall through which extends a combustion chamber 11. To the mouth of the combustion chamber 11 is secured a combustion cham-

ber 12. The connection between the combustion chamber 11 and the combustion chamber 12 is preferably such as to form a path for the flame which is more or less smooth or in a stream line so as to avoid any obstruction to the flame. Any means may be provided for connecting the combustion chamber 12 to the furnace or other chamber 11 in which combustion takes place. This may take the form of a ring 13 secured to the sheath 14 which in turn is mounted on and secured to a shoulder 12a on combustion chamber 12. Otherwise sheath 14 is spaced from the combustion chamber 12, so as to provide an air passage 15 between the sheath 14 and the combustion chamber 12. Heat insulation 16 may be provided between the ring 13 and the furnace wall 10 and chamber 11, if desired, to prevent undue radiation of heat to the sheath 14 and associated mechanism, the purpose of which will be hereinafter referred to.

The sheath 14 is shown formed so as to provide an annular enlargement 17 for the air passage 15. Connection between a blower 18 and the enlargement 17 is provided through an opening 19 in the sheath 14. The blower pipe 20 is preferably placed at an angle, as shown.

The combustion chamber 12 is shown conical in shape. However, it may be shaped like a tulip or like a morning-glory, that is with walls curving away from or toward the longitudinal center line, or it may be shaped otherwise if desired. The walls of the combustion chamber 12 are of course preferably without abrupt projections in order to avoid obstructions in the path of the flame.

35 The entrance of combustion chamber 12 is shown merging from a straight portion 22, illustrated as being cylindrical in character, but which of course may have any other desired shape. Portion 22 is shown provided with a collar 23 having a shoulder 24 to which is secured a sleeve 25 which fits over the end 26 of sheath 14 so as to provide a sliding fit. A packing nut 27 threadedly engages the sleeve 25, thus forming an air-tight sliding connection between sleeve 25 and sheath 14. Novel means is thus provided for absorbing the effects of unequal expansion between combustion chamber 12 and sheath 14.

40 Sleeve 25 is provided with an opening 29 in which is secured the end of tubular member 30 which in turn fits into an opening 31 in heating element chamber 32. Chamber 32 has an end 33 fitting over an air conduit 34 and is provided with threads 35 which accommodate a packing nut 36. Conduit 34 makes a reverse turn, as

illustrated at 38 and is connected to carburetor 39 as illustrated at 40.

Carburetor 39 may be of any standard construction. I have shown a carburetor having an outlet for the combustion mixture which will permit conducting the mixture in a straight line through the path in which it is to be ignited and consumed. However, any other arrangement may be provided.

10 The outlet of the carburetor is shown connected to the flange 23 so as to bring the outlet in line with the channel 41 in portion 22.

The general path of the air and eventually of the combustion mixture is therefore as follows:

15 The air enters from blower 18 into blower pipe 20, then passes through opening 19 into enlargement 17 of air passage 15, then into the more

restricted portion of air passage 15, then in between sleeve 25 and extension 22, then upwardly

20 through tubular member 30 into chamber 32, then through air conduit 34 into carburetor 39 where

it is mixed with the fuel oil. From here the resultant combustion mixture passes into combustion chamber 12. After the device is in opera-

25 tion the air in passing around combustion chamber 12 is pre-heated. This pre-heating of the air, of course, materially assists in volatilizing the fuel oil at the carburetor. The arrangement of

the air passage about the combustion chamber 12 in combination with its general shape is dis-

30 closed and claimed in my co-pending application

Serial Number 492,132 filed October 29, 1930.

As a result of this arrangement the air is always

35 maintained at a temperature consistent with

most efficient operation but is always kept safely

below that which will cause pre-ignition, regard-

less of the quantity of fuel consumed. Briefly,

the point of maximum temperature of the air is

reached when the entire combustion chamber 12

30 is filled with flame. As the consumption of fuel

increases beyond this point the design of the

combustion chamber is such that the velocity of

the combustion mixture at the entrance of the

combustion chamber 12 is greater than the rate

45 of flame propagation backward toward the en-

trance. The result is that the source of the

flame travels to the left, as seen in Figure 1,

from right to left into the combustion chamber

12. In view of the divergence of the walls of

50 the combustion chamber 12 and the progres-

sively increasing cross-sectional area, the ve-

locity of the unignited combustion mixture be-

gins to decrease until a cross-section is reached

55 at which the velocity of the combustion mixture

is equal to the rate of flame propagation. As-

suming that each particle of the combustion mix-

ture is traveling at the same velocity, the point

at which the flame will start will be in some plane

outwardly in the combustion chamber 12, de-

60 pending upon the velocity of the combustion mixture at the entrance of the combustion chamber.

With an increase in the rate of combustion the

source of flame moves to the left in the combus-

tion chamber 12, as seen in Figure 1. Conse-

65 quently a smaller area of the combustion cham-

ber is exposed to the temperature of the flame.

This in turn tends to decrease the total quantity

of heat transferred from the combustion cham-

ber 12 to the air passing through the air passage

70 15. At the same time the quantity of air passing

through the air passage 15 is increased due to

the increased rate of combustion. This in turn

reduces the quantity of heat transferred per unit

75 of air. The result is that the air may have

a relatively high temperature at low rates of

burning when a high temperature is most needed, and may be made to fall off in temperature as the rate of combustion increases and as the temperature requirements decrease. This construction and the theory of operation are discussed in detail in my co-pending application above referred to.

To bring the air to a proper temperature for starting, I provide a heating element 45 in the path of the air. Any type of heating element 10 may be employed for this purpose. The one shown is conveniently arranged in chamber 32 and is secured in a socket 46 of insulating material which accommodates the screw base 47 of the element 45. One electrode 48 is shown connected to a bolt 49, passing through the base of the socket 46. The other electrode 50 is shown connected to metallic element 51 which passes around the socket 46 and contacts the metallic portion of the screw base of heating element 45, 20 as illustrated at 51. A cap 52 is conveniently provided for mounting the electrodes 48 and 50.

To place upon the fuel in the carburetor approximately the same pressure as that of the air entering the carburetor I provide an outlet 55 in air conduit 34 and connect this outlet through pipe 56 with the carburetor. By this arrangement the normal reduction in pressure of the air passing through venturi 57 will cause the proper amount of fuel to issue from jet or jets 58.

To avoid flooding of the carburetor due to faulty operation of the needle valve and/or float of the carburetor I provide an overflow 60 having its opening 61 of substantially the same height as the proper level of the fuel in the carburetor. 25 The overflow is connected to a sealed receptacle 62, by means of pipe 63. To make the pressure in the receptacle 62 substantially the same as that in the float chamber I extend the pipe 56 to the receptacle 62. This will permit free flow 40 of excess fuel from the float chamber by means of gravity through the overflow 60.

Although a reticulated diaphragm may be employed to prevent propagation of the flame back to the carburetor, I prefer to use a venturi, such 45 as illustrated at 70, for this purpose. This is because reticulated diaphragms, for instance those made from wire cloth, have a tendency to clog and choke, requiring frequent cleaning, and also have a tendency to burn out more or less quickly. 50 I find that for all practical purposes a venturi serves the purpose of a reticulated diaphragm, and in addition to this will not clog or choke, does not require cleaning, will not burn out, adapts the apparatus for finer adjustment and for adjustment over a wider range, and what is most important is interchangeable to adapt the apparatus for adjustment as to capacity.

Consider for instance an apparatus of a given size, equipped with a reticulated diaphragm. Assuming that the rate of flame propagation back toward the carburetor is 20 ft. per second, it is obvious that the velocity of the combustion mixture through the diaphragm should be over 20 feet per second in order to keep the flame from resting on the diaphragm and/or clogging or choking the same. This then may be regarded as the minimum velocity of the combustion mixture. Let us assume in this instance that the velocity of the combustion mixture through the 65 diaphragm when the device is operating at full capacity is 120 ft. per second. Now, for the same blower pressure, a venturi placed in the aperture holding the diaphragm will permit the passage of approximately the same quantity of air as the 70

plain aperture. The result is that at maximum capacity the velocity of the combustion mixture through the throat of a venturi of standard form may be made to rise as high as 190 ft. per second or more. A much wider range of regulation is thus provided for than in the first case. In the first case the burner may be operated between 20 and 120 ft. per second and in the second case it may be operated between 20 and 190 ft. per second.

Any type of venturi may be employed for this purpose. I prefer to make the venturi removable, thus making the device adjustable for various rates of burning and blower pressures. My experiments have shown that a venturi having diverging walls which define an angle of about 3 to 4 degrees with the longitudinal center line, operates very efficiently.

I find by experience that, even though a reticulated diaphragm is not employed between the venturi and the carburetor, the flame will be quenched before it reaches the carburetor. In other words, in my experiments the flame has been quenched in the throat of the venturi when shutting down. This I believe to be due to the fact that at very low blower pressures the air velocity at the carburetor jet or jets is so low as to be unable to raise sufficient fuel to form a combustible mixture. Also at low rates of burning the rate of flame propagation is decreased due to leanness of the mixture. However, if desired, a reticulated diaphragm may be placed between the venturi and the carburetor outlet. This reticulated diaphragm will not burn out because it cannot be reached by the flame during normal operation, and will not clog because ash and other residue cannot be formed upon it by the burning fuel. Any means may be provided for holding the venturi in position.

I find it very convenient to provide spark plug housings 73 between sleeve 25 and portion 22. Portion 22 is provided on opposite sides with an aperture 74 to permit passage therethrough of the ends 75 of electrodes 76. The venturi 70 is likewise provided with apertures 77 to permit the ends 75 to project into the path of the combustible mixture. Electrodes 76 may be conveniently made from spark plugs of the ordinary type by removing the electrode which extends inwardly from the end of the tubular metallic shell. Housings 73 may be provided with screw threads to accommodate the bases of the spark plugs. The apertures 77 are preferably placed slightly toward the diverging side of the venturi throat. This prevents positive ignition on the carburetor side of the throat and at the same time places the electrodes in a position in which they are not contacted by the flame under normal operation.

In operation the electrodes 76 are placed across any source of supply. This is ordinarily the secondary winding of an ignition transformer. Normally the spark jumps from one electrode 76 to the other. Should one of the electrodes become grounded or short-circuited the other electrode will continue in operation because the effect of grounding or short-circuiting one electrode is the same as connecting one side of the transformer winding to the device itself. The spark in this instance jumps from the remaining electrode 76 to the nearest point which may be the surface of the venturi 70 or the other electrode. The direct path between electrodes 76 should of course be the shortest.

As a part of the automatic starting and operating equipment I provide a thermostatic

switching device 78 of a well known type, which extends into the tubular member 30. This thermostatic switching device comprises two sealed tubes mounted on a rotating base, each tube containing a small quantity of mercury. One end of each tube contains spaced electrodes. The arrangement is such that when the mercury in the tube is in the end containing the electrodes a circuit is closed through the electrodes. The thermostat elements which rotate the base are so arranged that when they have been subjected to a predetermined low temperature the mercury in one tube flows into one of its ends to establish a circuit through its electrodes and when the thermostat elements have been subjected to a predetermined high temperature the mercury in the other tube flows into one of its ends to establish contact through its electrodes. In the interim the circuit through the electrodes of the first tube has been broken. In other words at low temperatures a circuit is closed through the first tube only, and at high temperatures a circuit is closed through the second tube only. The arrangement is such that the second circuit is closed before the first is opened.

A thermostatic switching device 79 similar to that shown at 78 is placed in the conduit 34 at 80. In other words there is one thermostatic switching device on each side of the heating element 45. The operation of the heating element 45 will be hereinafter described.

Carburetor 39 is provided with a fuel inlet pipe 81 connected to any source of supply. Pipe 81 is provided with a valve 82. Carburetor 39 is also provided with a drain pipe 83 having a valve 84. Pipe 83 leads to any suitable receptacle not shown.

A tubular projection such as that illustrated at 85 may be provided to permit the insertion of a thermometer 86 into conduit 34 to determine the temperature of the air flowing therethrough.

The carburetor 39 is, of course, provided with the suitable butterfly valve 87.

Receptacle 62 is provided with a float 88 which controls an electrical switch 89 for establishing a circuit to electromagnetic valves 82 and 84. The arrangement is such that when the float 88 is at the bottom of the receptacle 62 a circuit is closed through the switch 89. When the float 88 raises, the circuit through switch 89 is broken. Fuel valve 82 opens with a flow of current and drain valves 84 closes with a flow of current and vice versa.

The thermostatic switching devices 78 and 79 and valves 82 and 84 together with the associated mechanism are part of the automatic starting and operating system and may or may not be used as desired.

The operation of the burner without the automatic starting and operating mechanism is as follows:

The carburetor float chamber is first drained of all fuel. The switches (not shown) leading to the heating element 45 and to a suitable transformer for electrodes 76 are now closed. The blower is started and the carburetor butterfly 87 is opened very slightly so as to permit only a small quantity of air to pass. In a very short time the air passing heating element 45 is heated to a temperature which is sufficiently high to cause vaporization of the fuel. The choke valve 65 is now partially closed. Fuel is then admitted into the carburetor float chamber. Ignition of the combustion mixture takes place almost immediately. The flame shoots outwardly from the venturi 70 into the combustion chamber 12, rais-

ing the temperature of the same. Heating of the combustion chamber 12 in turn heats the air passing through the air passage 15. The choke valve 65 can now be completely opened, thus placing it out of use. In a relatively short time the flame will furnish sufficient heat to the combustion chamber 12 to heat the air in air passage 15 to a temperature to permit operation without the help of heating element 45. Ignition having been well established, the switch (not shown) leading to the heating element 45 and to a suitable transformer may now be opened. The device is now properly warmed up and the amount of fuel consumed may be regulated by the carburetor valve 87. This regulation may be manual or automatic.

After the fuel reaches the proper level in carburetor 39 it begins to flow up into jet or jets 58 and is vaporized by the flowing air. The resulting combustible mixture is ignited as it passes through venturi 70 by the spark passing between electrodes 76.

The flame begins to heat combustion chamber 12 which in turn begins to heat the air passing through air passage 15. When the air passing through the air passage 15 reaches a desired temperature, suitable in itself for proper vaporization of fuel, it actuates thermostatic switching device 78 causing it to turn clockwise bringing the tubes 96 and 97 into the positions shown in dotted lines.

The turning of the thermostatic switching device 78 signifies that the device is properly warmed up and that the rate of combustion may be increased to meet requirements.

If, after the burner is in operation, the flame should become extinguished for any reason, combustion chamber 12 will begin to cool, thus failing to heat the air passing about it to the required temperature to hold thermostatic switching device 78 in its clockwise position. Thermostatic switching device 78 will then turn counterclockwise back to its starting position, opening the circuit through tube 97 which in turn breaks the circuits through fuel valve 82 and drain valve 84 causing the fuel valve 82 to close and the drain valve 84 to open. Flame extinction will cause thermostatic switching device 79 to return to its original position which will also break the circuit through valves 82 and 84.

Any irregularities in the float chamber of the carburetor causing excess fuel to overflow through pipe 60 into receptacle 62 will cause float 88 to rise, so as to open the circuit through valves 82 and 84 to shut off the supply of fuel and to drain the carburetor. The shutting off of the fuel supply extinguishes the flame and the device shuts down as described in the previous paragraph.

It can be readily seen that it is impossible to start and operate the device except under normal conditions. If any difficulty should arise, such difficulty must be entirely removed before the burner can be re-started. For instance, fuel difficulties causing the float 88 to rise in receptacle 62 requires the receptacle to be drained before switch 89 will be returned to normal position. The operator of course, will at once realize that the cause of the overflow of fuel must also be immediately corrected.

Ignition difficulties will prevent thermostatic switching device 78 from turning clockwise or will cause this thermostat to return to its original position, in either event the device will be shut down.

Failure of the heating element 45 will prevent thermostatic switching device 79 from turning

clockwise. This will prevent fuel from being delivered to the carburetor 39.

While the invention has been described in connection with liquid fuels it is understood that the same is applicable to burning of fuels of any character such as gaseous fuels or semi solid or solid fuels. The latter may be comminuted or volatile in character or otherwise.

Many other changes may be made in the hook-up or in other parts of the device without departing from the spirit of the invention. For instance thermostatic switching device 78 may be placed on the same side of the heating element as thermostatic switching device 79 by having thermostatic switching device 78 operate at a temperature above that capable of being supplied by the heating element but capable of being supplied by air passage 15.

My novel burner has been illustrated as operating in horizontal position. However, it is to be understood that it may operate at any angle provided the fuel mixing device is adapted thereto.

Having described my invention, it is obvious that many modifications may be made in the same within the scope of the claims without departing from the spirit thereof.

I claim:

1. In a device for burning fuel, a mixing chamber for air and said fuel, a combustion chamber for burning a mixture of said air and fuel, an air passageway in heat exchange relationship with said combustion chamber, a Venturi metering and mixing device for said fuel and air arranged in direct communication with said passageway so that the air flowing through said passageway and subject to the heat of said combustion chamber is the only air available and the only air used for operating, and carrying the resulting air and fuel mixture from, the metering and mixing device, a second venturi adjacent said combustion chamber and provided with associated ignition means, said last named venturi being adapted to prevent the passage of a flame therethrough, said venturis being substantially spaced from each other and said mixing chamber being arranged therebetween.

2. A device of the kind described, comprising a combustion chamber, means for forming a combustible mixture, said means comprising an inlet for fuel, a Venturi metering and mixing device for air and said fuel, an inlet for air and an air passageway subject to the heat of combustion in said combustion chamber, said metering and mixing device being in communication with said air passageway so that the air therein subject to the heat generated in said combustion chamber is the only air available and utilized for operating, and carrying the mixture from, said metering and mixing device, means for delivering said combustible mixture to said combustion chamber, and means for preventing flame propagation from said combustion chamber back to said combustible mixture forming means, said flame propagation preventing means comprising a venturi positioned in the path of said combustible mixture between said combustion chamber and said combustible mixture forming means, said venturi having a throat of a cross sectional area sufficiently small to increase the speed of said combustible mixture to a point at least as high as any rate of flame propagation of said combustible mixture during normal operation of said device.

3. In a device of the kind described, a combustion chamber, means for forming a combus-

- 5
tible mixture and for delivering the same to
said combustion chamber, said means comprising
an inlet for fuel, a Venturi metering and mixing
device for air and said fuel, an inlet for air
5 and an air passageway subject to the heat of
combustion in said combustion chamber, said
metering and mixing device being in communica-
tion with said air passageway so that the air
therein subject to the heat generated in said com-
bustion chamber is the only air available and
utilized for operating, and carrying the mixture
from, said metering and mixing device, a
second venturi between said first mentioned
10 means and said combustion chamber, said second
venturi positioned in the path of said combust-
ible mixture so as to cause all of said combustible
mixture to pass therethrough, said second venturi
15 preventing flame propagation therethrough
during normal operation of said device.
4. In a device of the kind described, a homogenizing chamber, means including a venturi for metering and mixing liquid fuel with air, an air passageway in heat exchange relationship with said combustion chamber, said venturi being in communication with said air passageway so that the air in said passageway subject to the heat generated in said combustion chamber is the only air available and utilized for operating, and carrying the mixture of air and fuel from, 10 said venturi, a second venturi adapted to prevent flame propagation therethrough during normal operation of said device, said homogenizing chamber interposed between and connecting said first and second mentioned venturis, and 15 means in said second venturi on the outlet side of the throat thereof for igniting said vaporized fuel.

JEROME J. SLOYAN.
